[57] CLAIM

The ornamental design for a wind-powered floating home, substantially as shown and described.

DESCRIPTION

FIG. 1 is a front view of a wind-powered floating home showing my new design;

FIG. 2 is a side elevational view thereof;

FIG. 3 is a rear elevational view thereof;

FIG. 4 is a rear elevational view thereof similar to FIG. 3, but with the sails in partially open position;

FIG. 5 is a top plan view thereof, and

FIG. 6 is a bottom plan view thereof.

FIG. 1

FIG.2

FIG.3

FIG. 4

FIG.5

FIG.6
